(57) **CLAIM**

The ornamental design for a side handle for cookware, as shown and described.

DESCRIPTION

FIG. 1 is a perspective view of the side handle for cookware showing my new design;

FIG. 2 is a right side elevation view thereof; the left side elevation view being the mirror image thereof;

FIG. 3 is a top plan view thereof;

FIG. 4 is a bottom plan view thereof;

FIG. 5 is a front elevation view thereof; and,

FIG. 6 is a rear elevation view thereof.

The broken lines in FIGS. 1, 2, 5 and 6 are for illustrative purposes only, depicting the environment of the new design, forming no part thereof as claimed.

1 Claim, 3 Drawing Sheets
